8 Claims. (Cl. 179—17)

This invention relates to a circuit arrangement for remote communication systems and more especially for telephone systems in which a plurality of lines extending in various traffic directions are in connection with a plurality of connecting paths by way of a common connecting line, leading to an exchange and a junction point in the latter. In the case of outgoing calls undesired switching-over operations in the connecting 5 devices of the exchange, caused by the speaking path to the calling subscriber's line not being completely established in due time, are prevented, and at the same time an efficient impulse transmission is ensured, in that a potential which is 10 connected up under the influence of a call initiating impulse, and serves to influence controlling means in the connecting devices, is disconnected after the call has been initiated in the exchange but not before the speaking line has been switched 15 through to the calling line.

The present invention is concerned with means for preventing disturbances in operation by influencing the controlling means in connecting devices of an incoming connecting path, while maintaining efficient impulse transmission in the case 20 of outgoing calls. This is accomplished according to the invention in that an auxiliary potential is applied to the connecting path of a line which is to be used in a speaking connection and which 25 is connected to the exchange by way of a connecting line common to other subscribers' lines, for the purpose of influencing controlling means (feeding bridges) in connecting devices in the exchange transitorily in the case of outgoing calls 30 and in the case of incoming calls throughout the duration of the latter.

By means of the arrangement according to the invention it is possible for this principle, which 35 renders efficient impulse transmission possible in the case of outgoing calls and consists in connecting up an auxiliary potential only transitorily in the case of outgoing calls, also to be used in systems in which the called subscriber can take 40 up and replace his receiver a number of times. On account of the auxiliary potential being connected throughout the duration of the incoming 45 call, the influencing of the feeding bridge in the incoming connecting path, which occurs when the receiver is replaced again after having been taken 50 up and causes undesirable switching operations, is effectively prevented.

In the embodiment so-called two-party line 55 systems are shown in which two subscribers' stations whose lines are brought together at a switching point are connected to a switching-over point

(US₂) by way of a common connecting line. The invention is, however, not limited to two-party line systems. It is also possible for more than two subscribers' lines to be associated at the switching-over point US₁, and also in place of 5 subscribers' stations, connecting lines, party lines or the like may be connected up.

In the drawings, Fig. 1 shows an arrangement of the invention, while Fig. 2 shows a modification thereof. 10

In the embodiments two subscribers' stations TS₁ and TS₂ are shown whose lines are connected to the switching-over point US₂ to the exchange devices in which an individual approach to preselecting devices (preselectors or call finders) is provided for each subscriber's station of 15 the two-party line. Intercommunication between the two subscribers of the two-party line is not possible.

The manner of operation of the arrangement 20 according to Fig. 1 is as follows: If a subscriber, for example, the subscriber at station TS₁ wishes to set up a call he takes up his receiver and thereby closes the circuit for relay R₁ in the switching-over point US₂: earth, battery, winding I of relay R₁, contact 1t₁, contact 2t₂, a-lead of the connecting line, winding I of relay U₁, contact 3u₂ 25 line to subscriber's station TS₁, contact 4u₂, winding II of relay U₁, contact 5u₁, earth. Relay U₁ which is situated in this circuit does not energize. Relay R₁ is energized, however, at the switching-over point US₂ and by closing its contact 6r₁ connects earth to the a-lead over contact 1t₁, while over contact 8r₁ battery through choke-coil Dr₁ is connected to the b-lead. The preselector VW₁ is accordingly set in motion in 30 known manner. When it finds a free group selector GW relay T in the preselector is energized in the known manner and switches through the line to the group selector over contacts 9t and 10t. 35 Relay T₁ at the switching-over point US₂ is accordingly energized over the circuit: earth, battery in the group selector, a-lead, preselector VW₁, contact 9t, winding I of relay T₁, contacts 6r₁ and 7t₁ and earth. Relay T₁ locks up over 40 contact 11t₁ and resistance W₁ and its winding II. Blocking potential is connected to the final selector approach of the second subscriber over contact 15t₁ so that this is protected against incoming calls. Moreover, the opening of contact 45 12t₁ and the closing of contact 13t₁ effects the switching-over of the junction at the switching-over point US₂. By the closing of contact 14t₁ the battery potential connected to the a-lead in the group selector GW operates directly on relay 50 55

U₁ at the switching-over point US₁. Relay U₁ is accordingly energized and opens its contact 5u₁ and closes its contact 15u₁ so that the speaking path is switched through at the switching-over point US₁.

Meanwhile, the slow operating relay R₁ has finally released at the switching-over point US₂ and by closing contact 16r₁ has switched through the b-lead of the speaking line to the group selector in a metallic circuit while shunting condenser C₁. Since contacts 6r₁, 8r₁, 17r₁, and 18r₁ are now open there are now no switching means associated with the speaking path which are capable of distorting the impulses.

Corresponding operations are brought about when a call is initiated from the subscriber's station TS₁. While a call is in progress from one subscriber's station the other subscriber's station is completely disconnected from the connecting line on account of the opening of contacts 3u₂ and 4u₂ or 19u₁ and 20u₁.

In the case of incoming calls, for example to subscriber TS₁, a circuit is established for relays R₁ and T₁ after the final selector has tested on the appropriate contact: earth in the final selector LW, c-lead, winding II of relay R₁, contact 21t₂, winding II of relay T₁, battery, and earth. Relays R₁ and T₁ energize in this circuit. By closing contact 14t₁ relay T₁ switches through the a-lead of the speaking line while the switching-over of the junction is effected by the closing of contact 13t₁. In order to prevent undesired switching operations from being brought about in the preceding selecting device GW if, in contrast to the conditions obtaining in the case of individual subscribers' outgoing calls, wherein the loop is not immediately closed when the subscriber calls, because the switching over device on switching over points US₁ and US₂ must first be operated, an auxiliary potential is applied to the b-lead of the connecting line over contact 8r₁: earth, battery, choke coil Dr₁, contact 8r₁, b-lead to the final selector. By this means, the criterion for "toll knock down" is prevented from being produced in preceding selecting devices GW. This auxiliary potential remains operative throughout the duration of the incoming call. For the purpose of balancing the subscriber's line a choke coil Dr₂ is connected over contact 17r₁, while over 22r₁ and the choke coil Dr₃ earth potential is applied to the b-lead of the connecting line leading to the switching-over point US₁. When the called subscriber replies relay U₁ energizes over the earth applied by way of contact 5u₁ and locks up after closing its contact 15u₁ over contact 22r₁ and the choke coil Dr₃.

On the release of the connection relays U₁ and R₁ deenergize on account of the release of the final selector LW. Moreover, relay T in the preselector is connected in parallel with the relay T₁ (winding II) so that this also returns to its rest position and the switching-over devices are accordingly restored to normal.

The second embodiment is differentiated from the first only in the construction of the switching over point US₂, the difference being in the arrangement of the bridge for connecting the auxiliary potential which in this case consists only of the choke coils Dr₁, Dr₂ or Dr₃, Dr₄. The b-lead of the speaking line is permanently switched through at the switching-over point US₂ in a metallic circuit. On initiating an outgoing call auxiliary potential is connected to the b-lead of the line over contact 8r₁ and the choke

coil Dr₁ on the energizing of relay R₁, as in Fig. 1, and remains connected up until relay R₁ releases when the speaking path is finally switched through to the calling line.

In the case of incoming calls relays R₁ and T₁ are energized over winding II, as in Fig. 1. Over contact 8r₁ relay R₁ connects auxiliary potential to the b-lead and thus prevents the transmission of the criterion for "toll knock down". In place of a second winding of relay R₁ a special auxiliary relay H₁ can be provided which connects the auxiliary potential to the b-lead over its contact h₁ and the choke coil Dr₁. The further switching operations correspond to those in Fig. 1.

In order to ensure the energizing of relay T₁, winding II of this relay can in the case of outgoing calls be connected over resistance W₁ and contact 22r₁ so that it is pre-magnetized without being energized. When the switching through to the group selector GW takes place only a small amount of energy is necessary to cause the relay T₁ to energize over its winding I. Also in the case of incoming calls the energizing of relay T₁ can be ensured in a special manner if a third low resistance winding is provided in the incoming c-lead in series with winding II, this facilitating the energizing of relay T₁ over its winding II.

What is claimed is:

1. In a telephone system, a common line, telephone lines branched from one end of said common line, connecting lines branched from the other end of said common line, switches in each connecting line for extending calls from said telephone lines, means responsive to an incoming call over either connecting line or an outgoing call on one of said telephone lines for taking said common line and one of said connecting lines into use to the exclusion of the other telephone line and connecting line, switching means in said connecting line operated responsive to the call to apply an auxiliary potential to the connecting line to influence the switches thereon, said switching means operated transitorily responsive to an outgoing call and for the duration of an incoming call.

2. In a telephone system, a common line, a pair of telephone lines branched from one end of said common line, a pair of connecting lines corresponding to said telephone lines branched from the other end of said common line, switches in each of said connecting lines for extending calls, means responsive to an incoming call or an outgoing call for taking the common line and one of the connecting lines into use to the exclusion of the other telephone line and connecting line, a relay in the connecting path taken into use, said relay operated momentarily in the case of an outgoing call and continuously in the case of an incoming call, and means controlled by the operation of said relay for applying a particular potential to the connecting line in order to control the operation of the switches on the connecting line.

3. In a telephone system as claimed in claim 2 in which the switching through of the connecting line the common line and the telephone line in a loop circuit to the associated switches is interrupted transitorily by the relay responsive to an outgoing call and responsive to an incoming call for the duration of the same.

4. In a telephone system as claimed in claim 2 in which the common line telephone line and connecting line are switched through in a loop circuit to the associated switches and in which the relay connects the auxiliary potential transi-

5 torily to the line in the case of outgoing calls and for the duration of an incoming call, and in which in the case of the incoming call the auxiliary potential and the breaking of the loop circuit to the switches takes place at the time when the connecting line corresponding to the wanted telephone line is engaged.

5. In a telephone system, a common line, a pair of telephone lines branched from one end of said 10 common line, a pair of connecting lines branched from the other end of said common line, switches in each of said connecting lines for extending calls, means responsive to a call for taking one of said telephone lines the associated connecting 15 line and the common line into use, said lines adapted to be switched through in a loop circuit to the associated switches, a relay in the connecting line operated transitorily responsive to an outgoing call and for the duration of an incoming call, said relay connecting an auxiliary 20 potential to the connecting line and interrupting the loop circuit extending to the switches in order to effect a control of the same, said relay operated in the case of an incoming call over the 25 testing circuit for the connecting line and in the case of an outgoing call over one side of the connecting and telephone lines.

6. In a telephone system as claimed in claim 5 in which the other telephone line and the other connecting line are disconnected from the common line when the first telephone and connecting lines are engaged in a call, and in which said other telephone and connecting line is guarded 5 from seizure on an incoming call while said first lines are in use.

7. In a telephone system as claimed in claim 5 in which a further auxiliary potential is applied 10 by the relay to one side of the connecting line responsive to an outgoing call in order to initiate the operation of the switches, and in which the said further auxiliary potential is disconnected by an auxiliary relay operated responsive to an incoming call. 15

8. In a telephone system as claimed in claim 5 in which a further potential is applied by the relay to one side of the connecting line responsive to an outgoing call in order to initiate the 20 operation of the switches, and in which the said further auxiliary potential is disconnected by an auxiliary relay operated responsive to an incoming call, said auxiliary relay operated over the incoming testing circuit simultaneously with said 25 first relay.

FRITZ WOLF.
